UNITED STATES PATENT OFFICE.

JOHN S. WORTH AND CHARLES BEECHT, OF COATESVILLE, PENNSYLVANIA, ASSIGNEES TO JOHN S. WORTH AND WILLIAM P. WORTH, BOTH OF COATESVILLE, PENNSYLVANIA.

CAR END.

1,172,096.

Specification of Letters Patent. Patented Feb. 15, 1916.

Application filed January 23, 1915. Serial No. 3,891.

To all whom it may concern:

Be it known that we, JOHN S. WORTH and CHARLES BRECHT, citizens of the United States, and residents of Coatesville, county 5 of Chester, State of Pennsylvania, have invented certain Improvements in Car Ends, of which the following is a specification.

One object of our invention is to improve the construction of the metallic ends of rail-way cars of the "box" type so that they will 10 withstand the pressures to which they are subjected.

A further object of the invention is to construct the end from metal plates pressed 15 into shape to form girders and to reinforce the plates between the girders.

These objects we attain in the following manner reference being had to the accompanying drawings, in which:

20 Figure 1 is a view in elevation of a car end illustrating our invention; Fig. 2 is a plan view; Fig. 3 is a side view; Fig. 4 is a sectional view on the line *a—a*, Fig. 1; Fig. 5 is a view in elevation illustrating a 25 modification of the end shown in Fig. 1; Fig. 6 is a plan view of the end illustrated in Fig. 5; Fig. 7 is a side view of the same; Fig. 8 is a sectional plan view on the line *b—b*, Fig. 5; and Figs. 9 and 10 are views 30 illustrating different modifications of the corrugations of the plates.

In the present instance, the car end consists of four plates connected on lines radiating from a common center below the floor of 35 the car and at the point where one plate joins another. A rib or beam is formed at each joint for strengthening the car end and the plates between the several beams are corrugated for the purpose of strength- 40 ening the plates.

Referring in the first instance to Figs. 1 to 4 inclusive, 1, 1 are the two plates which form the center of the end of the car and 45 2, 2 are the side plates. These plates are triangular in shape and have short trans- 50 verse corrugations 3 arranged at a slight angle, preferably at a right angle to the line of division between the center plate and the side plates, as shown. These plates are at the corners where strength and stiffness 55 are required and as the corrugations are comparatively short, the strength of the plates is materially increased. The corner plates are preferably much heavier than

the center plates, as it is desirable in cars 55 of this type to have the lower portion of the body of the car much stronger than the upper portion although, in some instances, the plates may be all of the same thickness. The plates 1, in the present instance, have 60 a series of radial corrugations 4, the center corrugations of each plate extending substantially the full length thereof and the side corrugations terminating at the points shown. By this construction, the plates are 65 comparatively narrow at the lower portion and, consequently, can be made of light material as they are strengthened by the ribs or beams where they are narrow and where they are wide, as at the upper end, they do 70 not require so much strength as there is very little pressure, if any, on the end plates of a car at this point. Each meeting edge of each plate has a deep rib 5, extending substantially the full length of the plate on 75 each side to the meeting edge and forming a strengthening beam and beyond the rib is a flat edge 6. The flat edge of one plate overlaps that of an adjoining plate and the two plates are secured together by a line of 80 rivets, as shown, and, by preference, these flat portions do not extend to the full depth of the plate but stop short a sufficient distance so that the inner heads of the rivets will not project beyond the inner surface 85 of the plates, as clearly shown in Fig. 4.

By the above construction, a substantial double beam is formed at each joint and the beams are preferably deeper on the lower half of the plate than on the upper half, as 90 shown in Fig. 3, thus adding additional strength to the lower half of the car end where strength is required. Each of these beams is rounded at the lower end so as to make a neat finish where the end is attached 95 to the platform structure of the car and the upper ends of the beams merge into the plates a short distance from the upper end thereof, as illustrated in Fig. 3. By locating the beams at the edges of the plates they 100 are formed without drawing the metal to any appreciable extent and under ordinary circumstances where a beam is pressed from the middle of a plate it weakens the material at the beam, due to the drawing action. 105 The beams in applicants' case are formed more by the bending action than by drawing.

While we have shown the center plates 1

having radial corrugations, they have transverse corrugations, as in Fig. 5, and the triangular side plates may have radial corrugations, as shown in Fig. 5, instead of those shown in Fig. 1.

In Figs. 5 to 8 inclusive, we have illustrated a modification of the invention showing the particular arrangement of the ribbed plates and in this instance, the three beams 1^a are pressed up at the extreme edge of the plates 1^a and 2^a and the edge of one plate overlaps the edge of another and the two portions form the beam, the edges being riveted at this point. This construction can be employed where the radiating beams are single instead of double, as in Fig. 1.

In Fig. 9, we have shown another modification in which a single rib is illustrated at the joints and both the center plates and the side plates have radiating corrugations varying in length.

In Fig. 10, we have illustrated still another modification in which an inclosing rib 3^a extends continuously around each plate 2^a in the form of a triangle with intervening ribs 3^b in the space within the triangle.

We claim:

1. The combination of an end plate for a freight car consisting of four sections, the outer sections being wider at the base than at the upper end and the two central sections being wider at the upper end than at the base, the central sections being joined by

a series of vertical rivets and the side sections being joined to the central sections by a series of rivets.

2. The combination of an end plate for a freight car made in four sections, the two outer sections being wider at the base than at the upper end and the two central sections being wider at the upper end than at the base, the sections being united by rows of rivets and each section being reinforced at the joints by ribs pressed up from the plates extending parallel with the rows of rivets.

3. An end plate for a freight car made in four sections, each section being substantially the full height of the car, the outer sections being wider at the base than at the upper ends and the two central sections being wider at the upper ends than at the base, the sections being secured together, the edges of one section lapping over and secured to the edges of another section; and reinforcing ribs struck up from the plates and extending parallel with said edges, each of said plates having reinforcing ribs extending from side to side of the plate.

In testimony whereof, we have signed our names to this specification, in the presence of two subscribing witnesses.

JOHN S. WORTH.
CHARLES BRECHT.
